UNITED STATES PATENT OFFICE.

JAMES A. DORAN AND JOSEPH G. DORAN, OF PROVIDENCE, RHODE ISLAND.

PROPELLER PENCIL.

Application filed October 19, 1921. Serial No. 508,794.

To all whom it may concern:

Be it known that we, JAMES A. DORAN and JOSEPH G. DORAN, citizens of the United States, residing at Providence, in the county 5 of Providence and State of Rhode Island, have invented certain new and useful Improvements in Propeller Pencils, of which the following is a full, clear, and exact description.

10 The object of this invention is to provide a propeller pencil of few parts, simple and durable in construction, inexpensive to manufacture, and so constructed as to be relatively small in diameter and neat in appearance.

Moreover, by our construction, all soldered, brazed or other insecure joints may be eliminated, and the structure materially strengthened, thus producing a pencil entirely 15 free from the most usual causes of failure in service.

The invention consists in a propeller pencil having an outer casing within which are mounted and completely enclosed all of the 20 working parts of the pencil; these working parts comprising a guide member carried by a support having a press fit within the casing, a projector member adapted for longitudinal sliding movement within the guide member but held thereby against rotation, and a propeller member comprising a rotatable cylindrical tube screwthreaded throughout a portion of its length and furnishing, in its unthreaded portion, a magazine 25 for extra pencil leads, the projector member being provided with a screwthreaded portion or head adapted to cooperate with the screwthreaded portion of the propeller member, whereby upon rotation of the propeller member the projector member will be given a longitudinal sliding movement to project the lead held in the guide member to operative position beyond the point of the pencil, all as will be hereinafter explained 30 and finally claimed.

In the accompanying drawings illustrating the invention, in the several figures of which like parts are similarly designated, Figure 1 is a central longitudinal section

showing the preferred form of the invention. Fig. 2 is an elevation of the casing, a portion thereof at the top being broken away to show the interior. Fig. 3 is a top view of the casing of Fig. 2. Fig. 4 is an elevation of the projector member assembled. Fig. 5 is a top view thereof. Fig. 6 is a section taken in the plane of line 6—6, Fig. 4. Fig. 7 is an elevation, and Fig. 8 is a top view of the guide member and its support assembled. Fig. 9 is an elevation of the propeller member. Figs. 10 and 11 show, respectively, an elevation and a top view of an octagonal casing which may be used instead of the cylindrical casing of Figs. 1 and 2, if desired. Figs. 12 and 13 are, respectively, an elevation and a top view of the guide member and its support as used with the casing of Fig. 10. Figs. 14 and 15 are, respectively, an elevation and a top view of a modified form of guide member and support in which a square tube is used. Fig. 16 is a section taken in the plane of line 16—16 of Fig. 14. Fig. 17 is a sectional view of a cap made of sheet metal. Fig. 18 is a sectional elevation showing a modified form of cap in which an eraser is provided, and a protecting cover therefor. Fig. 19 is a sectional view of a cap provided with an eraser but without a protecting cover. Fig. 20 illustrates a pocket clip and the means of attaching it to the pencil casing. Fig. 21 is a section taken in the plane of line 21—21 of Fig. 20. Figs. 22 and 23 illustrate a modified form of cap and magazine end in which screwthreading is dispensed with. Figs. 24 and 25 illustrate, respectively, a sheet metal cap and a solid metal cap, each provided with a ring.

Referring particularly to Figs. 1 to 9 inclusive, the pencil comprises a casing 1 of cylindrical cross-section, having a reduced or tapered lower or point portion 2. The interior of this casing is fluted or grooved as shown at 3, Figs. 1, 2 and 3.

Within this casing adjacent to its lower end is mounted a guide member comprising a tube 4 reduced or tapered at its lower end 5 and provided with slits 6 to form spring fingers providing a spring or friction grip to

firmly hold the lead 7 in adjusted position and against slipping outwardly. The upper end of the tube 4 is squared and fitted in a squared hole in the center of a support 8, 5 said upper end extending through the support and being clinched as at 9 to securely hold the guide to the support in a unitary structure. This clinching also forms a sort of bell-mouth to the squared opening thus 10 provided in the tube, for a purpose later appearing.

The periphery of the support 8 is fluted or grooved as shown at 10, to match the grooving 3 of the casing, and the support is 15 of such diameter as to make a press fit within the casing. Therefore, when the support and guide member are assembled in the casing, the press fit of the support therein will prevent displacement of the guide longitudinally of the casing, and the interengaging 20 grooving or fluting 3 and 10 will prevent relative rotation between the parts.

Working within the guide 4 and having an easy sliding fit within the squared portion thereof is a projector member comprising a rod 11, square in cross-section, and having its lower end reduced to form an end 12 circular in cross-section and of such diameter as to pass through the opening at 30 the point of the pencil to fully eject the lead therefrom. It will be noted, also, that the end of the reduced portion is rounded to facilitate its passage through the spring fingers of the guide tube 4 and through the 35 opening of the pencil point. On the upper end of this rod 11 is mounted a screw-threaded member 13 having a central bore 14, Fig. 1, of such diameter as to receive the square portion of the rod 11 extending 40 part way into it, the remainder of the length of the bore being reduced in diameter as at 15 and the rod 11 having a correspondingly reduced portion to fit therein, the end of the rod being headed over into a counter- 45 sunk recess as shown at 16 to unite the rod 11 and screwthreaded member 13. In order that there may be no relative rotation between the rod 11 and member 13, the shank 17 of the member is flattened against the 50 rod, as shown at 18.

It will thus be seen that, although the projector member 11 may slide longitudinally of the guide member 4, it can not rotate therein because of the fit with the 55 squared upper portion of the guide member.

The desired longitudinal movement, whereby the lead is propelled, is imparted to the projector member 11 by means of a propeller member comprising a cylindrical 60 tube 19 provided throughout a portion of its length with an internal screwthread 20 with which the screwthreaded member 13 of the projector cooperates. The unthreaded portion of the tube provides a magazine 21 for the storage of extra pencil leads, the

bottom of this magazine being defined by a cupped partition 22 having a press fit within the tube 19 and being held against upward movement by means of a bead 23 formed in the tube just above the upper cup-edge of 70 the partition 22. In addition to its function as a bottom for the magazine 21 this partition also acts as a stop to limit the upward movement of the projector member.

The tube 19 is of such diameter as to 75 have an easy rotative fit within the casing 1 and is provided adjacent to its upper end with a circumferential groove 24, Figs. 1 and 9, into which the end 25 of the casing 1 is turned to form a lip engaging the groove 80 to thus secure a rotative inseparable connection between the casing and the propeller member.

Above the groove 24 is a tapered shoulder 85 26 and above this shoulder the tube is screw-threaded externally as at 27 to receive a cap 28 for closing the end of the magazine 21. This cap 28 is complementally recessed as at 29 to fit over the shoulder 26 and thus 90 limit the threading of the cap upon the tube. When the cap is screwed down upon the shoulder 26 the frictional grip of the tapered surfaces is sufficient to permit reverse rotation of the propeller member 19 for the purpose of replenishing the lead without premature unscrewing of the cap 28. Moreover, this frictional grip prevents accidental unscrewing and loss of the cap.

The pencil is assembled as follows:— 100 First the guide member 4 is pressed into position in the lower portion of the casing 1, as above described, then the screwthreaded member 13 of the projector is threaded part way into the tube 19. With the projector and propeller members thus assembled, they are slipped into the casing 1, the end 12 of the rod 11 being entered in the opening of the tube 4. It will be apparent that the bell-mouth construction of this opening 105 greatly facilitates the entering of the end of the rod therein. With the rod thus entered in the guide the propeller member is manipulated so as to cause the square portion of the rod 11 to slip into the guide tube 4. This allows the propeller member 110 to slip into the casing so that the end 25 of the casing may be spun or otherwise turned into the groove 24. Thus all the parts of the pencil are held in operative position 115 with respect to each other.

In order to insert a lead in the pencil, the projector is retracted within the guide member until the screwthreaded member 13 abuts against the partition 22, then a lead is inserted in the pencil point and pressed upon firmly and evenly until it is completely inserted in the guide tube 4. The propeller member is then rotated until sufficient of the lead is projected from beyond the pencil point to provide a writing point. As this 120 125 130

point wears down the lead may be further projected.

The spring fingers formed by the slits 6 in the end of the guide tube at all times exert a frictional hold upon the lead and prevent it from slipping out of the pencil.

Referring now to Figs. 10 to 13 inclusive, we show a modification of our invention in which, instead of the cylindrical casing of 10 circular cross-section, we may use a casing polygonal in cross-section, and a complementary support 30, Figs. 12 and 13, on the guide tube. When such a casing and support are used the necessity for fluting or grooving 15 the inner surface of the casing is avoided, since relative rotation of the casing and guide is prevented. All the other members of the pencil are the same for the polygonal casing type as for the circular cylindrical casing type, and are assembled 20 in the same manner.

It may be desirable to substitute a tube 31 of square or other non-circular cross-section for the guide tube 4, and in Figs. 25 14, 15 and 16 we have illustrated such a substitution. In such case the end of the tube is tapered and reduced to circular exterior cross-section, as shown at 32, as before, but, because of the square interior cross-section 30 of the tube 31, it is necessary to add a circular friction member to completely embrace the lead, and this is done by soldering, brazing or otherwise securing an eyelet 33 to the end of the tube 31, this eyelet being 35 provided with slits 34 to form the friction fingers. The upper end of the tube 31 is inserted in the squared opening of the support 8 and split and clinched over thereon, as shown at 35.

40 When pencils of this character are provided with casings and caps of precious metal, it is desirable to make as great a saving of such metal as possible, and to this end instead of making a cap of a solid 45 piece, as shown in Fig. 1, and then boring and tapping it, we prefer to make the cap by drawing it from sheet-metal. Such a cap is shown in Fig. 17.

It is sometimes desirable to provide this 50 type of pencil with an eraser, and our construction lends itself readily to such provision. In Fig. 18 we illustrate one form that the pencil may take when provided with an eraser, in which the cap 36, corresponding to cap 28, is a mere shell and is 55 apertured at its top to allow one end of the eraser 37 to project through it, the eraser being provided at its other end with a shoudered base 38 adapted to rest upon the end 60 of the propeller tube 19 and be thereby supported when the eraser is used. A dust cap 39 is made to fit snugly with a frictional grip upon the cap 36 to protect the eraser when not in use, and if desired, to increase 65 the grip, the interior of the dust cap may

be grooved as indicated at 39' and the exterior of the cap 36 complementally grooved.

In Fig. 19 we show the provision of an eraser in a cap of the type shown in Fig. 1, the eraser being in all respects similar to 70 that of Fig. 18 and being supported upon the end of tube 19 when the cap is in position.

In Fig. 1 the pencil is shown as provided with a pocket-clip 40 soldered, brazed or 75 welded to the casing 1, but inasmuch as one of the objects of the invention is to eliminate soldered or other insecure joints or unions between parts of the pencil, we have devised a more secure means of attaching the 80 clip, as shown in Figs. 20 and 21. This comprises slitting the casing to provide a strap 41 which is raised slightly out of the plane of the casing, and under this strap two tongues 42, formed on the clip 43, are 85 projected, the strap and tongues being thereafter clinched to form a secure union between the casing and clip.

If desired, the screwthread 27 on the end 90 of tube 19, and the complementary screwthread in the cap 28 may be dispensed with, and these parts provided instead with grooves or flutes 44 (as shown in Figs. 22 and 23) adapted to frictionally hold the 95 cap in place and insure rotation of the propeller member when the cap is rotated.

As shown in Figs. 24 and 25 the cap 28 may be provided with a ring 45 by means of 100 which the pencil may be attached to a chain or the like.

From the foregoing it will be apparent that we provide a propeller pencil of exceptionally strong and simple construction and of very few parts, there being, in effect, only five parts in all, viz:—the casing, the 105 guide member, the projector member, the propeller member and the cap, and all are strong and durable and without soldered or other insecure joints or connections. Moreover, as above pointed out, we are able to 110 produce by our construction, pencils of small diameter and size, such as are commonly known as programme or jewelers' pencils, and having lead magazines which, so far as we are aware, has been impossible 115 with pencils of this type as heretofore constructed.

Although we have herein shown and described a number of forms in which the invention may be embodied, it is to be understood that we do not consider it as limited to such embodiments, as various other changes may be made in details of construction and arrangement of parts without departing from the spirit of the invention 120 or the scope of the following claim.

What we claim is:—

In a pencil, a guide member comprising 130 a tube having a reduced portion at its lower end provided with slits forming spring

fingers for frictionally engaging the pencil leads, the upper end of said tube being of non-circular cross-section, and a support provided with a corresponding non-circular aperture to receive the end of said tube, the tube extending through said support and having its end clinched thereupon to form a unitary structure.

In testimony whereof we have hereunto set our hands this 11th day of October, A. ¹⁰
D. 1921.

JAMES A. DORAN.
JOSEPH G. DORAN.
